PHYSICIAN'S INSTRUMENT CABINET

Earl W. Claus, Kirkwood, Mo., assignor to Shampaine Company, St. Louis, Mo., a corporation of Missouri

Application March 19, 1953, Serial No. 24,117

Term of patent 14 years

(Cl. D33—19)

To all whom it may concern:

Be it known that I, Earl W. Claus, a citizen of the United States, residing at the city of Kirkwood, county of St. Louis, State of Missouri, have invented a new, original, and ornamental Design for a Physician's Instrument Cabinet, of which the following is a specification, reference being made to the accompanying drawing, forming a part thereof, in which:

Figure 1 is a perspective view of a physician's instrument cabinet embodying my new design when viewed from one side; and

Figure 2 is a perspective view thereof when viewed from the other side.

The back wall not shown in Figures 1 and 2 is plain and unornamented.

I claim:

The ornamental design for a physician's instrument cabinet, substantially as shown and described.

EARL W. CLAUS.
